UNITED STATES PATENT OFFICE.

ELOF NELSON, OF OAK CREEK, COLORADO.

BAKER'S FURNACE.

1,292,017.

Specification of Letters Patent.

Patented Jan. 21, 1919.

Application filed June 13, 1918. Serial No. 239,859.

To all whom it may concern:

Be it known that I, ELOF NELSON, a citizen of the United States, residing at Oak Creek, in the county of Routt and State of Colorado, have invented certain new and useful Improvements in Bakers' Furnaces, of which the following is a specification, reference being had to the accompanying drawings.

10 This invention relates to bakers' furnaces, and has for its primary object to provide a baker's furnace with a double chambered baking oven, and means for effecting an equal distribution of the heat from the furnace to the oven chambers when both chambers are being used.

15 It is another important object of my invention to provide means for radiating and controlling the heated air so that the baking chambers of the oven will be heated throughout their areas to a substantially uniform temperature.

20 The invention also has for an additional object to provide a baker's furnace as above characterized which will be exceedingly strong and durable in its construction, and in the use of which highly satisfactory results may be obtained in the baking of bread, pastries and like products.

25 30 With the above and other objects in view the invention consists in the improved construction, combination and arrangement of the several parts as will be hereinafter more fully described, subsequently claimed and 35 illustrated in the accompanying drawing in which similar reference characters designate corresponding parts throughout the several views, and wherein:—

Figure 1 is a vertical sectional view 40 through a baker's furnace and oven constructed in accordance with the preferred embodiment of the invention;

Fig. 2 is a transverse section taken on the line 2—2 of Fig. 1; and

45 Fig. 3 is a similar section taken on the line 3—3 of Fig. 1.

Referring in detail to the drawing, 5 designates the front wall of the furnace, 6 the rear wall thereof, 7 the top wall, and 8 the 50 base wall. These furnace walls may be of any desired construction and if preferred may be suitably reinforced and insulated in any approved manner.

55 A fire box 9 is centrally disposed between the side walls of the furnace structure, and at its front end communicates with a trans-

versely extending chamber 10, which chamber is in communication with the longitudinally extending chambers 11, said chambers receiving the smoke and products of combustion and conveying the same to a vertical passage or flue 12 in the rear wall 6 of the furnace structure.

Spaced floors or decks 13 are suitably mounted and secured within the upper portion of the furnace and extend the full length and width thereof, said floors separating the interior of the furnace into upper and lower baking chambers 14 and 15 respectively. The top wall of the fire box 70 9 extends substantially the entire length of the furnace and between said wall and the lower floor or deck 13, a horizontal metal wall 16 is arranged and suitably supported upon the side and end walls of the furnace. Between the top of the fire box and the wall 16, a partition wall of masonry indicated at 17 is disposed, said wall separating the smoke passages or chambers 11 from each other. The space between the 80 horizontal metal wall 16 and the floor 13 of the lower baking chamber 15 constitutes a hot air chamber 18. At the rear end of the furnace structure between the wall 16 and the floor 13, a bridge wall 19 is disposed and is provided with a plurality of ports or openings 20 communicating with a vertical flue 21 which is disposed within the smoke flue 12. This flue extends upwardly along the rear wall 22 of the oven 90 proper. The top wall 23 of the oven is spaced from the top wall 7 of the furnace structure to provide a longitudinally extending passage 24 over the oven which is in communication with the smoke flue 12. 95 At its forward end the passage 24 communicates with the smoke stack 25, through the ports or openings 27 in a bridge wall 26. Preferably, suitable braces or stays 28 are arranged at intervals between the top wall 100 of the furnace and the top wall 23 of the oven, and similar braces 29 are also arranged between the horizontal wall 16 and the floor plate 13 of the lower oven chamber 15.

A feed door 30 for the fire box 9 is arranged in the rear wall 6 of the furnace structure, and suitable doors 31 are also mounted in the front wall of the furnace to afford access to the respective oven chambers. These doors are equipped with suitable air inlet valves. I may also provide

one or more valved air inlet pipes 32 in communication with the hot air chamber 18 so that the temperature in this chamber may be suitably regulated.

5 33 indicates a collecting hood arranged at the top of the front wall of the furnace in communication with the smoke stack 25. 34 designates a sliding damper plate for the purpose of opening and closing communication 10 between the passage 24 and the stack 25. This plate is provided with a suitable operating rod indicated at 34' extending forwardly at one side of the hood 33.

The side walls 35 of the furnace structure 15 are formed with the passages 36 therein, which are in communication at their lower ends of the hot air chamber 18. These passages extend substantially the entire length of the furnace walls and upwardly to a point 20 substantially midway between the floor 13 of the baking chamber 14 and the top wall of the furnace. At this point the furnace walls are provided with ports or openings 37 to afford communication between the respective chambers 36 and the baking chamber 14. An additional series of ports or 25 openings 38 are also provided in each side wall of the furnace and afford communication between the chambers 36 and the other baking chamber 15. A damper plate 39 and 30 40 is provided for each of the ports 37 and 38 respectively. These damper plates are mounted for sliding movement in suitable guides 41 and to each of the series of damper plates a rod 42 and 43 respectively is secured, said rods at one of their ends being movable through the front wall of the furnace structure and provided with suitable hand holds whereby they may be conveniently 35 operated. The rear wall 22 of the oven proper is also provided with two series of ports or openings 44 and 45 respectively communicating with the respective oven chambers 14 and 15 to admit the heated air 40 from the flue 21 into the rear ends of these chambers. These two series of openings as 45 well as the longitudinally extending series of openings 37 and 38 are preferably arranged in different vertical planes alternately with respect to each other.

From the above description, it will be readily understood that the heat and products of combustion from the fire box 9 passing rearwardly through the chambers 11, 55 causes the metal wall 16 to become very highly heated, the wall of the flue 21 being likewise heated in the upward passage of the products of combustion to the flue 24. The heated air radiates through the chamber 18 and upwardly into the chambers 36 in the side walls of the furnace structure. If both oven chambers are being used, the operator opens both series of dampers 39 and 40 through the medium of the rods 42 and 43 so that the hot air will be admitted

in uniform volume into the two oven chambers at spaced points throughout the length thereof. This will result in the heating of these oven chambers to a substantially uniform temperature. While I have not 70 herein illustrated damper plates for the openings 44 and 45 in the rear wall of the oven, it will be understood that if desired such damper plates may be provided. By means of my improved furnace structure, it 75 will be seen that the full heat value of the smoke and products of combustion is utilized in the heating of the oven chambers, while at the same time all possibility of the smoke or gas finding its way into the baking chambers of the oven is obviated. The heating of these chambers can also be regulated and the chambers heated to the requisite degree, by the proper adjustment of the sliding damper plates. 85

From the foregoing description taken in connection with the accompanying drawing, the construction, manner of operation and several advantages of my improved baker's furnace will be clearly and fully understood. The invention provides a relatively simple and very substantial construction for high capacity bakers' ovens which may be installed at relatively small cost and in the operation of which considerable economy 95 may be realized in the consumption of fuel. While I have referred to but two baking chambers, it is manifest of course that a greater number of such chambers might be employed as desired by an obvious extension 100 or duplication of the structure described. The improved furnace is also susceptible of a great many other modifications in the form, proportion and relative arrangement of its several parts and it is therefore to be understood that I reserve the privilege of adopting all such legitimate changes as may be fairly embodied within the spirit and scope of the invention as claimed. 105

I claim:—

1. In a furnace of the character described, a furnace structure, a fire box extending substantially the entire length thereof, a double chambered oven above the fire box and a hot air chamber immediately below the oven, 115 said furnace structure having spaced longitudinally extending passages communicating with the forward end of the fire box to convey the smoke and products of combustion in contact with the wall of the hot air chamber to an outlet, and means for independently controlling the admission of hot air from said chamber into the respective oven chambers. 120

2. In a furnace of the character described, 125 a furnace structure, a fire box extending substantially the entire length thereof, an oven above the fire box and a hot air chamber between the oven and the fire box, a longitudinally extending partition wall between the 130

- top of the fire box and the bottom wall of said hot air chamber, said partition wall providing spaced longitudinal passages in communication with the fire box to receive the 5 products of combustion, said furnace structure having an outlet stack and communicating flues extending along the top and rear walls of the oven and in communication with said passages.
- 10 3. In a furnace of the character described, a furnace structure, a fire box extending substantially the entire length thereof, a baking oven within the upper portion of the furnace structure and a hot air chamber extending the entire length and width of the 15 furnace between said oven and the fire box, the rear wall of the oven having a vertical
- flue in communication with said hot air chamber and the interior of the oven, said structure being provided with outlet passages for the products of combustion in communication with the forward end of the fire box and extending along the hot air chamber, a smoke stack at the forward end of the furnace and flues extending along the top 25 and rear walls of the oven and affording communication between said passages and the stack.
- In testimony whereof I hereunto affix my signature in the presence of two witnesses. 30
ELOF NELSON.
